(57) **CLAIM**

The ornamental design for a strap fitting for girth straps of an equestrian saddle, as shown and described.

DESCRIPTION

FIG. 1 is a front perspective view of a strap fitting for girth straps of an equestrian saddle showing my new design.

FIG. 2 is a top plan view thereof, the bottom plan view being a mirror image thereof.

FIG. 3 is a side elevational view, the opposite side elevational view being a mirror image thereof.

FIG. 4 is a top plan view thereof; and,

FIG. 5 is a bottom plan view thereof.
